UNITED STATES PATENT OFFICE

2,520,091

HOSIERY

Willy de Mond, Hollywood, Calif., assignor to
 Sanson Hosiery Mills, Inc., Philadelphia, Pa.,
 a corporation of Delaware

Application April 7, 1950, Serial No. 154,682

9 Claims. (Cl. 66—178)

1

This invention relates to hosiery. More particularly, it is concerned with plain knitted (as distinguished from rib knitted) full length or ladies fine gauge or sheer stockings produced from synthetic yarn such as nylon, which can be set by heat treatment incident to boarding for capacity to withstand subsequent launderings without undergoing change in shape.

The chief aim of my invention is to increase the elasticity of stockings of the kind referred to, while at the same time rendering them more resistive to snagging and laddering.

These objectives I have attained in practice, as hereinafter more fully disclosed, by forming the stockings after they have been shaped by boarding in the usual way, with lengthwise extending accordion pleats, and subjecting them while pleated, to the action of steam at the temperature and pressure sufficiently high for a time interval of the proper duration to permanentize the folds.

In the finished relaxed stockings, the crease lines resulting from the pleating produce a corrugated or fluted effect which is highly ornamental and attractive, said crease lines disappearing, however, upon expansion of the fabrics as the stockings are drawn on to the legs of the wearers.

Other objects and attendant advantages will appear from the following detailed description of the attached drawings, wherein—

Fig. 1 is a view in side elevation of a wale-wise pleated stocking conveniently embodying my invention.

Fig. 2 shows a fragment of the fabric of the stocking.

Fig. 3 is a diagrammatic fragmentary cross sectional view of the pleated fabric showing it in its normal relaxed condition.

Fig. 4 is a view similar to Fig. 3 showing how the pleats disappear upon transverse expansion of the fabric as the stocking is drawn into the leg of the wearer.

Figs. 5 and 6 are views like Figs. 1 and 2 of an alternate embodiment of my improved stocking in which the pleats extend on a bias to the wales of the fabric.

Figs. 7 and 8 are views in turn like Figs. 1 and 2 showing still another alternative embodiment in which the stocking is pleated on a bias in opposite directions.

The stocking exemplified in Fig. 1 will be observed as being of the shaped or full fashioned type such as is ordinarily produced in a continuous operation on a straight knitting machine, the same having the usual closed welt 9, a re-

2

inforced "cradle" foot 10, and a back seam 11 extending from its top edge to the toe tip. It is to be understood that in accordance with my invention, the stocking of Fig. 1 is plain knitted and, as shown, is in this instance permanently pleated lengthwise, the pleats or flutings 12 being defined by sharp crease lines and appearing as relatively shallow ridges which extends outwardly and inwardly of the fabric F as diagrammatically shown at 13 and 14 in Figs. 2 and 3 when the fabric is relaxed, the apices of said ridges lying, for the most part, wale-wise of the fabric as indicated by the correspondingly numbered broken vertical lines in Fig. 2 and intersecting the fabric courses at right angles.

It will be seen that the pleats create a highly pleasing aesthetic appearance in the stocking, and although permanently set into the fabric, disappear entirely upon lateral expansion of the

20 fabric as the stocking is drawn onto the leg of the wearer. Moreover the permanently bent loops along the ridge lines or creases 13 and 14 tend to render the fabric more resistive to snagging or laddering.

25 In the alternative embodiment of Figs. 5 and 6, the pleats 12a are disposed at an angle or on a bias relative to the wales of the plain-knitted fabric of the stocking with creation likewise of an attractive appearance. As a consequence of per-

30 manent bending the fabric loops of different wales along the broken lines 13a, 14a representing the ridges of the pleats in Fig. 6 which extend at an angle to both the fabric wales and courses, the modified stocking is rendered even 35 more resistive to snagging and laddering than in the first described embodiment of Figs. 1 and 2 as will be readily understood.

In either of the two above exemplified cases, the pleats may be produced by laying the stockings flat, after boarding, between two strips of paper or other suitable sheet material, and running the assemblage through a suitable crimping or pleating machine. After having passed 40 through the crimping machine, convenient lengths of the pleated paper strips with the stockings folded between them are rolled up and separately wrapped in sheets of plain paper. The rolls so prepared are next placed in a treating chamber such as is ordinarily used in pre- 45 boarding nylon stockings, and while in the chamber, subjected to the action of steam at a pressure and temperature sufficiently high to insure permanent setting of the folds in the fabric. Finally, after treatment in the chamber for the 50 requisite time interval, the rolls are withdrawn 55

and, after being allowed to cool somewhat, are opened up and the stockings removed from between the enclosing layers of the crimped mold paper and assume the attractive appearance described of them in connection with Figs. 1 and 5.

The further modified stocking shown in Fig. 7, is characterized by having pleats 12b extending in opposite directions with creation of a checked or diamond pattern which is defined by uniformly spaced crease lines 15b crossed upon the crease lines 13b, 14b as in Fig. 8. This effect is secured simply by running the stocking, after it has been pleated in one direction and set like the stocking of Fig. 5, through the pleating machine a second time, properly laid flat between other mold paper sheets to predetermine pleats at an angle to those formed during the first pass through the machine. The second setting operation in the treating chamber is however carried out with steam at a temperature and pressure somewhat lower than in the first instance to prevent elimination of the pleats previously produced. The plain-knitted fabric of the stocking of Fig. 7 is of course also rendered more elastic transversely by the crossed pleats as well as more resistive to easy snagging and laddering like the stocking of Fig. 5.

In the alternative embodiments of Figs. 5 and 7, the welts, feet and back seams are identified by the same numerals used in Fig. 1, with addition of the letter "a" and "b" respectively however for convenience of more ready distinction.

While I have particularly described my invention by reference to plain flat knitted fashioned stockings, it is not necessarily confined to such stockings alone, since plain-knitted seamless stockings of nylon can be finished in the same manner after boarding with attainment of like advantages.

Having thus described my invention, I claim:

1. As a new article of manufacture, a stocking plain-knitted from nylon and accordion pleated, the pleat-defining creases being permanently set into the fabric at an angle to the fabric courses and visible when the stocking is relaxed, but disappearing as the stocking is drawn onto the leg of the wearer.

2. A stocking according to claim 1, wherein the pleats extend in the direction of the length of the stocking.

3. A stocking according to claim 1, with pleats in crossed relation and with the respective pleat-defining creases at an angle to both the fabric wales and courses.

4. As a new article of manufacture, a stocking with a turned welt at the top, and a reinforced cradle foot, plain-knitted from nylon and accordion pleated throughout, the pleat-defining creases being permanently set into the fabric at an angle to the fabric courses and visible when the stocking is relaxed, but disappearing as the stocking is drawn onto the leg of the wearer.

5. A stocking according to claim 4, wherein the pleats extend generally in the direction of the length of the stocking.

6. A stocking according to claim 4 with pleats in crossed relation, and with the respective defining creases at an angle to both the fabric wales and courses.

7. As a new article of manufacture, a longitudinally-seamed fashioned stocking plain-knitted from nylon and accordion pleated, the pleat-defining creases being permanently set into the fabric at an angle to the fabric courses and visible when the stocking is relaxed, but disappearing as the stocking is drawn onto the leg of the wearer.

8. A stocking according to claim 7, wherein the pleats extend generally in the direction of the length of the stocking.

9. A stocking according to claim 7, with pleats in crossed relation, and with the respective defining creases at an angle to both the fabric wales and courses.
